CASKET LOWERING DEVICE

Ernest H. Kaiser, Chicago, Ill., assignor to Frigid

Fluid Company, a corporation of Illinois

Application May 6, 1947, Serial No. 746,334

4 Claims. (Cl. 254—136)

1

This invention relates to casket lowering devices of the type used in cemeteries to lower a casket into a grave.

In using a casket lowering device, the casket is placed on flexible straps which are wound on longitudinally extending winding shafts. When the funeral director releases the mechanism, the weight of the casket causes the shafts to unwind under the control of a délicate speed governor provided in one of the supporting posts of the device. It is very important in a mechanism of this type that its movement be very smooth and free from vibration. It must start and stop without noise or jerkiness. Frequently the ground or structure surrounding the grave is not level, and one or more of the supporting posts may be slightly out of alignment.

The primary object of the present invention is to provide an improved mechanism in which the governor is controlled by a manually operable friction brake which will positively lock the device, when desired, and will permit the governor to start and stop very smoothly when the control handle is turned.

A further object of the invention is to provide end shafts having a universally jointed portion to permit accommodation to small variations in the level of the supporting posts, so that if the posts are not level the shafts will not throw the gearing in the governor out of alignment and interfere with its operation.

A further object of the invention is to provide an improved fastening and bearing support for the end housing in which the end shaft is mounted, so that even though the posts are not level there is no danger of jamming the gears in the posts.

The invention is illustrated in a preferred embodiment in the accompanying drawings in which:

Figure 1 is a plan view of a casket lowering device embodying the invention; Fig. 2, a fragmentary top plan view of the governor mechanism; Fig. 3, a fragmentary elevational view of the governor shown in Fig. 2; Fig. 4, a vertical sectional view, taken as indicated at line 4—4 of Fig. 2; Fig. 5, a vertical sectional view, taken as indicated at line 5—5 of Fig. 2; Fig. 6, a vertical sectional view, taken as indicated at line 6—6 of Fig. 2; Fig. 7, a fragmentary vertical sectional view, taken as indicated at line 7—7 of Fig. 1, and Fig. 8, a sectional view, taken as indicated at line 8—8 of Fig. 7.

In the embodiment illustrated, the casket lowering device has four supporting corner posts 9 which contain cast bearing frames 10, which are enclosed in an ornamental housing 11. A pair of telescopic winding shafts 12 are secured to shafts 13 which extend into and are antifrictionally journaled in the bearing frames 10.

2

The shafts are provided with winding spools 14 for the flexible straps 15.

The posts are connected at each end by a telescopic non-rotatable housing 16, as best shown in Figs. 1, 7 and 8. Round nuts 17 are secured in each end of the housing and are adapted to fit into a recess 18 provided in the bearing frame 10. A threaded bushing 19 has an enlarged head to hold an antifriction bearing 20 inside of the post. The bushing extends through an opening in the frame 10, to engage the nut 17 and clamp the housing securely to the post. A stud shaft 21 extends through the bushing and is supported by the bearing 20 and at its outer end by an anti-friction bearing 22. It is provided with a bevel gear 23, which meshes with a bevel gear 24 provided on one of the winding shafts 12. The shaft 21 is held against longitudinal movement by collars 25 having set screws 26. One end of the shaft 21 makes a driving connection with a hollow square shaft 27, by means of rivets 28 and 29 which are arranged perpendicular to each other and impale loosely enlarged holes in the shaft 21. This provides a limited flexible or universal joint that will accommodate itself to slight variations in the alignment between the shaft 21 and the square shaft 30 which extends into the post having the speed governor. The shaft 30 makes a telescopic connection with the hollow square shaft 21, and is provided with a spring-pressed button 31 which bears against the inside of the shaft 21. A notch 32 is provided, by striking outwardly a portion of the shaft 21, so that the housing 16 will not be over extended.

The two telescopic parts of the housing 16 have sufficient clearance to accommodate some variation in the level of the end posts. The inner sleeve of the housing 16 is provided with a series of apertures 33, which may be engaged by a spring-pressed pin 34 having a head 35 and slidably mounted in a bracket 36 which is riveted to the outer sleeve of the housing 16.

A similar arrangement is provided for the end housing in the end shaft at the opposite end of the device, and it will be understood that the end shafts and longitudinal winding shafts 12 are constantly kept in mesh by the bevel gears, regardless of the lateral or longitudinal adjustment of the device.

The governor is provided in the upper left hand post, as viewed in Fig. 1. In this post a special casting 37 is provided to carry the governor. A bevel gear 38, corresponding to the bevel gears in the other posts, has a rearwardly extending hub 38a which is keyed to the shaft 30 and is provided with ratchet notches 38b, to be engaged by pins 39 which impale the hub of a worm wheel 40, and are urged inwardly by a bow spring 41. The ratchet mechanism permits the shafts 12 to be turned manually to tension the

straps 15 without operating the governor. However, the governor prevents separate unwinding. The worm wheel 40 is in constant engagement with a worm shaft 42 which is antifrictionally journaled in the casting 37. The worm shaft 42 is provided at its upper end with a spur gear 43, which is in mesh with a spur gear 44 provided on the rotor 45.

The rotor is of conventional construction and has a pivotally mounted pair of fly weights 46, which may move outwardly by centrifugal force and raise a brake drum 47 upwardly against the action of a compression spring 48 into contact with an annular braking member 49 which is secured to a plate 50. The plate 50 is held in position by screws 51, and the braking member 49 is secured to the plate by means of adjustable bolts 52.

The braking drum 47 also has a circumferentially disposed braking surface 53, which is adapted to be engaged by a soft braking shoe 54, preferably made of felt, carried by an arm 55 which is pivotally mounted on the base, as indicated at 56, and is urged out of engagement with the brake drum by means of a spring 57. The brake 54 may be moved into contact with the brake drum by means of a hand lever 58 which has a self-locking plate 59 journaled in the casting 37 and engaged by an adjustable set screw 60. A compression spring 61 is provided on the inner end of the shaft and is urged by a nut 62 into engagement with the inner face of the casting 37 so as to limit the outward axial movement of the hand lever 58.

In using the device, it is adjusted and placed so as to frame the grave. After the end housings have been locked by means of the pins 34, the winding shaft 12 may be wound up on the spools 14 by manual rotation. This is permitted by the ratchet on the worm wheel 40. The straps may be further tensioned by placing a crank on the upper end 63 of the worm shaft which is accessible to a hole 64 in the cover of the governor. At the burial services a casket, indicated by dotted lines in Fig. 1, is placed on the straps, and when the handle 58 is raised the brake 54 will permit the rotor to turn, because of the pressure of the worm wheel 40 on the worm shaft 42. The speed of the rotor is controlled by adjustment of the brake surface 49, but the speed may be further reduced or stopped at any position by the hand lever 58.

The foregoing detailed description is given for clearness of understanding only, and no unnecessary limitations should be understood therefrom, for some modifications will be obvious to those skilled in the art.

I claim:

1. A casket lowering device, comprising, four supporting corner posts, a pair of telescopically adjustable longitudinally disposed winding shafts antifrictionally journaled in said posts, a pair of telescopically adjustable tubular housings connecting the end posts, a pair of telescopically adjustable end shafts within said tubular housings antifrictionally journaled in said end posts, bevel gears in each of said posts making a positive driving connection between said winding shafts and end shafts, said end shafts having a flexible universal-jointed portion to provide accommodation to small variations in the level of the corner posts, said universal-jointed portion including a stub shaft in a corner post, said stub shaft having an end extending loosely into one of said end shafts, and a pair of laterally spaced apart

pin members fixed at right angles to each other in the adjacent end of the end shaft, said shaft extending end having a pair of apertures loosely receiving said pin members.

5 2. A casket lowering device as claimed in claim 1, in which the inner one of said telescopically adjustable end shafts has a slidable pin, spring means for urging said pin outwardly so that its outer end will engage the inner surface of the outer one of said telescopically adjustable end shafts for sliding longitudinally therewith, a shoulder on said outer one against which said pin will strike so that the housing will be prevented from being over-extended, the outer ones of said 10 end shafts having a longitudinal opening substantially larger in cross dimension than the cross dimension of the stub shaft extending end, to enable rotation of the end shaft and stub shaft when out of longitudinal alignment with each other.

15 3. In a casket lowering device, a corner post, a pair of telescopically adjustable tubular housings connected with said post, a pair of telescopically adjustable end shafts within said tubular 20 housings, a bevel gear in said post, a shaft journaled in said post and on which shaft said bevel gear is fixed to rotate therewith, and a flexible joint connecting said shaft in the post with one of said end shafts for accommodating small variations in the level of the post, said flexible joint comprising a pair of laterally spaced pin members extending loosely through an end of said post shaft, said pin members being fixed in the outer 25 one of said end shafts, said end of said post shaft being substantially smaller than the outer one 30 of said end shaft to provide universal swinging movement therebetween.

35 4. A casket lowering device, comprising, four supporting corner posts, a pair of telescopically adjustable longitudinally disposed winding shafts antifrictionally journaled in said posts, a pair of telescopically adjustable tubular housings connecting the end posts, a pair of telescopically adjustable end shafts within said tubular housings 40 anti-frictionally journaled in said end posts, bevel gears in each of said posts making a positive driving connection between said winding shafts and end shafts, said end shafts having a flexible universal-jointed portion to provide accommodation 45 to small variations in the level of the corner posts, the end housing having a nut secured in its end portion, the corner post having an apertured socket to receive said end portion of the housing, and a flanged bushing extending through 50 said socket and having threaded engagement with said nut and clamping the housing to the post, said bushing having a socket within the post in which an anti-friction bearing is mounted for the end shaft which extends through the 55 housing and bushing.
